DESIGN FOR A STOCKING OR SIMILAR ARTICLE.

Substitute for design application Serial No. D. 20,620, filed February 4, 1927. This application filed July 8, 1927. Serial No. 22,697. Term of patent 14 years.

To all whom it may concern:

Be it known that I, SAUL SILVERMAN, a citizen of the United States, residing at New York city, in the county of New York and State of New York, have invented a new, original, and ornamental Design for a Stocking or Similar Article, of which the following is a specification, reference being had to the accompanying drawing, forming part thereof.

This application is filed as a substitute for the application filed by me on February

4th, 1927, under Serial Number D 20,620 for design for stocking or similar article, which application is being formally abandoned, for the reason that the drawing on file in said case is deemed insufficient to show applicant's true invention.

The drawing is a perspective view of a stocking showing my new design.

I claim:

The ornamental design for a stocking or similar article as shown.

SAUL SILVERMAN.
